UNITED STATES PATENT OFFICE.

BENJAMIN WALKER, OF LEEDS, AND ALFRED SPINK, OF HYDE PARK, LEEDS,
ENGLAND.

LOOM FOR WEAVING PILE FABRICS.

1,165,047.

Specification of Letters Patent. Patented Dec. 21, 1915.

Application filed April 25, 1914. Serial No. 834,337.

To all whom it may concern:

Be it known that we, BENJAMIN WALKER and ALFRED SPINK, subjects of the King of Great Britain, residing at 81 Leopold street, 5 Leeds, England, and 15 Pearson Terrace, Hyde Park, Leeds, England, respectively, have invented new and useful Improvements in or Relating to Looms for Weaving Pile Fabrics, of which the following is a specification.

This invention relates to looms for weaving pile fabrics and it relates particularly to looms for weaving warp pile fabrics and having the pile forming wires arranged longitudinally of the fabric.

In looms of this kind it has been proposed to have the pile forming wires fixed in such manner that their rear ends are movable and to move each said rear end by means of a 20 reed of special construction from one side to the other of the path followed by the end of pile warp pertaining to the wire, so that by moving the rear end of each wire from one lateral position to the other the warp 25 end pertaining thereto alternately passes down opposite sides of the said wire and thereby the loops are formed without displacing the pile warp from its vertical path.

The chief object of the present invention 30 is to provide a loom of the above stated kind in which the parts are adapted to be moved accurately and without danger of injuring the warps.

According to this invention means are 35 provided whereby the rear end of each pile forming wire is locked in its lateral position. During the forming of the loops the pile forming wires are liable to be moved downward, or sag, at their rear ends, and to take 40 this up means are provided for carrying the said ends upward to their normal position vertically—that is to say, for bringing the rear ends of the wires into alinement and thereby insuring that all the pile forming 45 wires are firmly supported at one level during the time the pile ends are being formed over the said rear ends. After being raised to their normal position the rear ends of the wires are locked. The rear ends of the said 50 wires are adapted to move between stationary vertical guide blades or members each arranged between the vertical paths of the pile warp ends, the end of each pile forming wire is moved laterally from one side to the 55 other of the path of the pile warp end per-

taining thereto by means of a deflector. The stationary vertical guide blades or members between which the pile wire ends are moved are provided with resilient, or yielding, or movable sections against which the wire ends 60 come in contact, when the said sections yield sufficiently to cause the non-contacting side of the pile wire to become approximately flush or in alinement with the non-movable portions of the stationary vertical guide 65 blades or members thus insuring the pile wire being taken up by and locked within the locking device.

In the accompanying drawings:—

Figure 1 is a side elevation, partly in section, of one construction of warp pile loom according to this invention. Fig. 2 is a front elevation of a portion of the same, certain parts being removed. Figs. 3 and 4 are respectively a vertical section and a plan showing, on a larger scale, some of the wires and certain parts pertaining thereto. Figs. 5 and 6, 7 and 8, and 9 and 10 are respectively side and front elevations showing the parts in their various positions that they assume 80 during working. Figs. 11 and 12 are respectively side and front elevations, on a larger scale, of one of the stationary guide blades or members.

The side frames 2, the reed 3 and the lay 4 85 carried on swords 5 on the rocking shaft 6 and actuated from the crank shaft 7 by connecting arms (not shown), the tappet shaft 8, the supporting plate 9, the take-up roller 10 provided with the usual pins and the take-up roller 12 for the piece, and the cutters 13 90 are of ordinary construction.

The figuring-warp ends α and α' are controlled by a figuring-harness comprising cords b and actuated by suitable jacquard 95 or other mechanism. The binder warp ends c and c' and the stuffer warp ends e are controlled respectively by heddles d and f in the usual manner. In Fig. 1 and also in Fig. 3 the acting figuring-warp end α' is shown 100 fully opened or lifted higher than the ordinary binder warp end c' . The pile ends are shown as being operated from jacquard mechanism as is used for weaving a figured carpeting but when it is used to weave plain 105 carpeting the pile ends may be controlled by a heddle or heddles operated by the ordinary harness levers in a dobby head, cams or any other of the various methods known to those skilled in the art of weaving. 110

The pile forming wires 13 are arranged longitudinally of the fabric and extend rearwardly so as to more or less penetrate the spaces between stationary vertical guide blades or members 14 located immediately 5 behind the ordinary reed 3 when such reed is in its extreme backward position, as shown in Fig. 1.

At the front of the supporting plate 9 is 10 a stationary cross-rail 15 provided with a recess 16 along its front edge. The front ends of the longitudinal pile wire 13 which are each provided with a downwardly projecting end or hook 17 are loosely mounted 15 between this cross-rail and a cross angle-plate 18 detachably secured to the cross-rail 15.

The upper and lower ends of the guide blades or members 14 are mounted in fixed 20 spacing frames 19 extending across the loom and each comprising a back bar 21 and a front bar 20. The guide blades or members are separated the desired distance apart, that is to say, the pitch of the pile wires is 25 adjusted, by projecting pins 22 secured in each back bar 21, and the blades or members are held in position by the front bar 20 detachably secured to the back bar. The said fixed spacing bars and their guide 30 blades or members form a kind of fixed reed. The rear ends of the longitudinal pile forming wires are adapted to be moved laterally against the opposite sides of the guide blades or members 14 of this fixed 35 reed.

Mounted immediately in front or at the front edge of each guide blade or member 40 14 is a vertical guide wire 26 the upper portion of which is cranked or provided with a crank or deflector 27. These cranks are automatically operated from projecting arms 45 28 on the said wires 26 engaging with the dents of a reed 30 having a transversely reciprocating movement and so arranged as 50 to be capable of moving each crank laterally from its central or mid position to either side of same and at the same time moving the free ends of the pile wires laterally. Also mounted immediately behind or 55 at the rear edge of each guide blade or member 14 is preferably a wire slide 32 provided with thin sheet metal flanges 33 projecting in front of and embracing the guide blade or member and forming as a whole a locking-slide 31. This locking-slide is capable 60 of being moved vertically up and down and is so arranged that when it is in its top or locking position the side flanges inclose a partly cut away or thin portion in the guide blade. This thin portion is preferably cut away and a thin flat wire 36 substituted and 65 loosely mounted near the front edge of the guide blade in sockets formed in the top and bottom of the opening or notch formed in the guide blade. This thin flat wire or mov-

able section 36 is adapted to move a little laterally when a pile wire is moved and pressed against same by the crank of either adjacent guide blade causing the non-contacting side of the pile wire to become flush 70 or within the main portion of the guide blade thus insuring the pile wire being passed by and locked between the side flanges of the locking-slide.

The side flanges 33 of each locking-slide 75 31 are preferably connected together at the front edges by a connecting piece 40 thus providing a "lifter" for raising the wire vertically into its normal position.

The locking-slides are moved vertically 80 up and down through the medium of a recessed cross-bar 42 into which recess the hooked ends 43 of the slides project. The cross bar 42 is weighted by suitable springs or weights.

The reed 30 may be transversely reciprocated by a flexible connection or cord or chain 44 passing over and under guide pulleys 45 and 46 respectively connecting said reed to the lever 47 operated by the 90 suitable cam or tappet 48 on the shaft 8. The reed is returned or moved in the opposite direction by a returning spring or a hanging weight connected to the reed by the cord 50. Suitable stops are provided 95 for limiting the movement of the reed.

The weighted bar 42 for moving the locking-slides 31 up and down is connected by cords or chains 52 to the ends of cranked levers 53 coupled together by the connecting 100 rod 54, one of the levers being provided with an arm 55 to which a cord 56 is attached, the cord passing under the guide pulley 57 and connected at its other end to the lever 58 operated by the suitable cam 105 or tappet 60 on the shaft 8.

A reciprocating motion may be imparted to the reed 30 or the weighted bar 42 by means of a jacquard hook or by any other suitable means.

In operation the pile warp ends are raised at the required time above the pile wires through the medium of the jacquard mechanism. The cranks or deflectors press the rear ends of the pile wires when free laterally against the right or left hand sides of the thin flat wires or movable sections and the connecting pieces or "lifters" raise the wires to their normal position to be locked in this position by the projecting side 115 flanges of the locking slides, after this the cranks are returned to their central or mid position against the sides of the locked up wires thus leaving clear spaces between the pile forming wires for the pile warp ends 120 to pass down on the opposite sides of the said wires and thereby form the loops over same without displacing the said ends from their vertical paths.

In Figs. 1, 3 and 4 the pile wires are 130

shown as being pressed against the left hand sides of the guide blades and with the locking slides down, and in Figs. 5 and 6 the wires are shown as being locked in this position and with the cranks returned to their central or mid position.

In Figs. 7 and 8 the pile wires are shown as being pressed against the right hand sides of the guide blades and with the locking slides down, and in Figs. 9 and 10 the wires are shown as being locked in this position and with the cranks returned to their central or mid position.

Claims:

- 15 1. In a loom for weaving pile fabrics the combination of pile-forming wires with their rear ends movable, stationary vertical guide members each arranged between the vertical paths of the warp ends, means for 80 moving the rear end of each pile-forming wire laterally from one side to the other of the path of the pile warp pertaining thereto, and means for locking the movable rear end of each wire in the lateral position to which 85 it has been moved.
- 20 2. In a loom for weaving pile fabrics the combination of pile-forming wires with their rear ends movable, stationary vertical guide members each arranged between the 90 vertical paths of the warp ends, means for moving the rear end of each pile-forming wire laterally from one side to the other of the path of the pile warp pertaining thereto, means for locking the movable rear end 95 of each wire in the lateral position to which it has been moved, and means whereby the movable rear end of each pile-forming wire is returned to its normal vertical position.
- 25 3. In a loom for weaving pile fabrics the 100 combination of pile-forming wires with their rear ends movable, stationary vertical guide members each arranged between the vertical paths of the warp ends, resilient sections in the said guide members against which sections the pile-forming wires come into contact on being deflected, and means for moving the rear end of each pile-forming wire laterally from one side to the other of the path of the pile warp pertaining thereto, 105 and means for locking the movable rear end 110 of each wire in the lateral position to which it has been moved.
- 30 4. In a loom for weaving pile fabrics the combination of pile-forming wires with their rear ends movable, stationary vertical guide members each arranged between the vertical paths of the warp ends, resilient sections in the said guide members against which sections the pile-forming wires come into contact on being deflected, means for moving the rear end of each pile-forming wire laterally from one side to the other of the path of the pile warp pertaining thereto, 115 and means for locking the movable rear end 120 of each wire in the lateral position to which it has been moved, 125 and means whereby the movable rear end of each pile-forming wire is returned to its normal vertical position.
- 35 5. In a loom for weaving pile fabrics the 130 combination of pile-forming wires with their rear ends movable, stationary vertical guide members each arranged between the vertical paths of the warp ends, a slide mounted upon each guide member and adapted to engage with the rear end of an adjacent pile-forming wire and to lock the same in the position to which it has been deflected, and means for actuating the said slides.
- 40 6. In a loom for weaving pile fabrics the combination of pile-forming wires with their ends movable, stationary wires with their rear ends arranged between the vertical paths of the warp ends, a slide mounted upon each guide member and adapted to engage with the rear end of an adjacent pile-forming wire and to lock the same in the position to which it has been deflected, and to return the same to its normal vertical 80 position.
- 45 7. In a loom for weaving pile fabrics the combination of pile-forming wires with their rear ends movable, stationary vertical guide members each arranged between the vertical paths of the warp ends, resilient sections in the said guide members against which sections the pile-forming wires come into contact on being deflected, and means for moving the rear end of each pile-forming wire laterally from one side to the other of the path of the pile warp pertaining thereto.
- 50 8. In a loom for weaving pile fabrics the combination of pile-forming wires with their rear ends movable, stationary vertical guide members each arranged between the vertical paths of the warp ends, resilient sections in the said guide members against which sections the pile-forming wires come into contact on being deflected, means for moving the rear end of each pile-forming wire laterally from one side to the other of the path of the pile warp pertaining thereto, and means for locking the movable rear end 105 of each wire in the lateral position to which it has been moved.
- 55 9. In a loom for weaving pile fabrics the combination of pile-forming wires with their rear ends movable, stationary vertical guide members each arranged between the vertical paths of the warp ends, resilient sections in the said guide members against which sections the pile-forming wires come into contact on being deflected, means for moving the rear end 110 of each pile-forming wire laterally from one side to the other of the path of the pile warp pertaining thereto, means for locking the movable rear end of each wire in the lateral position to which it has been moved, 115 and means whereby the movable rear end of each pile-forming wire is returned to its normal vertical position.
- 60 10. In a loom for weaving pile fabrics the combination of pile-forming wires with 120

combination of pile-forming wires with their rear ends movable, stationary vertical guide members each arranged between the vertical paths of the warp ends, a slide mounted upon each guide member and adapted to engage with the rear end of an adjacent pile-forming wire and to lock the same in the position to which it has been deflected, and means for actuating the said slides.

75 6. In a loom for weaving pile fabrics the combination of pile-forming wires with their ends movable, stationary wires with their rear ends arranged between the vertical paths of the warp ends, a slide mounted upon each guide member and adapted to engage with the rear end of an adjacent pile-forming wire and to lock the same in the position to which it has been deflected, and to return the same to its normal vertical 85 position.

7. In a loom for weaving pile fabrics the combination of pile-forming wires with their rear ends movable, stationary vertical guide members each arranged between the vertical paths of the warp ends, resilient sections in the said guide members against which sections the pile-forming wires come into contact on being deflected, and means for moving the rear end of each pile-forming wire laterally from one side to the other of the path of the pile warp pertaining thereto.

8. In a loom for weaving pile fabrics the combination of pile-forming wires with their rear ends movable, stationary vertical guide members each arranged between the vertical paths of the warp ends, resilient sections in the said guide members against which sections the pile-forming wires come into contact on being deflected, means for moving the rear end of each pile-forming wire laterally from one side to the other of the path of the pile warp pertaining thereto, and means for locking the movable rear end 110 of each wire in the lateral position to which it has been moved.

9. In a loom for weaving pile fabrics the combination of pile-forming wires with their rear ends movable, stationary vertical guide members each arranged between the vertical paths of the warp ends, resilient sections in the said guide members against which sections the pile-forming wires come into contact on being deflected, means for moving the rear end 115 of each pile-forming wire laterally from one side to the other of the path of the pile warp pertaining thereto, means for locking the movable rear end of each wire in the lateral position to which it has been moved, 120 and means whereby the movable rear end of each pile-forming wire is returned to its normal vertical position.

10. In a loom for weaving pile fabrics the combination of pile-forming wires with 130

their rear ends movable, stationary vertical guide members each arranged between the vertical paths of the warp ends, resilient sections in the said guide members against which sections the pile-forming wires come into contact on being deflected, means for moving the rear ends of each pile-forming wire laterally from one side to the other of the path of the pile warp pertaining thereto, means for locking the movable rear end of each wire in the lateral position to which it has been moved, and means whereby the

movable rear end of each pile-forming wire is returned to its normal vertical position and locked in the said position. 15

In testimony whereof we have signed our names to this specification in the presence of two subscribing witnesses.
